DENTIST'S CASTING MACHINE

Henry H. Samuels, Rustenburg, Transvaal,
Union of South AfricaApplication July 8, 1940, Serial No. 344,408
In Union of South Africa June 30, 1939

1 Claim. (Cl. 22—69.1)

This invention relates to improvements in casting machines and especially is concerned with a novel device useful in the casting of dental inlays, incasements, fillers, plates and the like.

Because the noble metals are especially resistant to corrosion and hence unaffected by oral conditions, and because gold is both the cheapest and the most commonly available of the noble metals, it is presently the practice to manufacture inlays, fillers, plates and other oral structures from gold usually by casting and it is devices useful for this purpose that the present invention is directed.

Experience indicates that in the casting of gold in molds having minute fissures, it is desirable that during the casting operation intermediate the pouring and solidification of the metal being cast positive pressure be applied to assure penetration of the fissures by the metal. In the past this has been accomplished by application of superatmospheric pressure to the melted metal while within the mold. This practice, however, has necessitated the use of relatively complicated and consequently expensive equipment with resultant expense which is made unnecessary by practice of the present invention.

It is an object of the present invention to provide means for materially increasing the pressure applied to molten metal within a mold resulting from heat exchange between superheated metal and adjoining materials whereby the metal is compressed within the mold assuring faithful reproduction of the mold outline.

Another object of this invention is to provide a convenient machine useful in the casting of gold inlays and the like which includes means both forcing the metal into minute fissures and which also serves to preclude or at least minimize loss of gold due to splattering while the gold is transferred into the mold.

Noteworthy among the advantageous features of the present invention are its simplicity and ruggedness of construction, the former suiting the device to the requirements of manufacture under conditions of mass production and the latter assuring long useful life.

Other objects and features of the new and improved dentists' casting machine according to the present invention will be apparent to those skilled in this art during the course of the following description.

Regarded in certain of its broader aspects the novel casting machine according to the present invention comprises a base whereon a casting ring can be rigidly mounted, a vertically reciprocable cap for said ring carried in a frame attached to said base, and means for facilitating the packing of said cap with moist melted fibrous material whereby, when said cap is pressed upon the casting ring, radiant heat of molten metal

within the casting ring causes vaporization of moisture in the matted fibrous material and the steam so produced forces the molten metal into minute interstices of the mold, the pressure continuing until the metal has solidified.

In order to facilitate a fuller and more complete understanding of the present invention a specific embodiment thereof herein illustrated will be hereinafter described, it being clearly understood, however, that the illustrated embodiment, although presently preferred, is provided solely by way of example of the practice of this invention and not by way of limitation thereof except insofar as the invention is recited in the 15 subjoined claim.

Referring then to the drawings,

Figure 1 is substantially a side elevational view of the presently preferred embodiment of this invention,

20 Fig. 2 is a top plan view of the device shown in Fig. 1,

Fig. 3 is essentially a vertical sectional view of Fig. 1 taken along the line 3—3 thereof,

25 Fig. 4 is essentially a horizontal sectional view of Fig. 1 taken along the line 4—4 thereof,

Fig. 5 is substantially a perspective view of the vertically sliding carriage forming part of the device illustrated in Fig. 1,

Fig. 6 is essentially a side elevational view of 30 the vertically sliding carriage showing a stirrup clamp mounted thereon for forming a fibrous mat in parts of the device as will be subsequently described,

Fig. 7 is essentially a front elevational view of 35 the assembly shown in Fig. 6, and

Fig. 8 is a side elevational view of the device partially in vertical section illustrating the disposition of parts of the device while in use.

Referring now to the drawings wherein the 40 presently preferred herein illustrated embodiment of this invention is generally designated by the reference character 10, it will be seen that the device comprises a base 11 supported on feet 12 disposed essentially in a horizontal plane and having a flat top surface from which extend essentially parallel guide bars 13 rigidly secured in the base by appropriate means such as threading or the like. A carriage 14 having fixedly mounted therein split sleeves 15 exteriorly tapered-threaded to receive rings 16 is mounted upon the standards 13, the rings and sleeves serving upon occasion to permit the holding of the carriage in a selected position with respect to the base. A lever 17 swinging upon an adjustable fulcrum 45 which comprises a pin 18 receivable in any one of a plurality of openings 19 formed in an upright member 20 mounted upon the base 11 by means of screws 22 is connected to the carriage 14 by means of ball and socket joints generally designated by the reference characters 23 and

24 uniting a link 25 with the arm and the carriage respectively. It is to be noted that the joint 23 comprises a ball 26 mounted upon a pin 27 secured to the lever arm by means including a nut 28 and that the joint 24 comprises a ball 29 carried on a pin 30 rigidly mounted on a central portion of the carriage 14. For purposes which will be hereinafter described posts 31 are provided near the corners of the carriage 14, the posts projecting upwardly from the surface of the carriage to a degree such that when the carriage is inverted the ball 29 carried on the pin 30 will clear a surface upon which the inverted carriage is placed. An upwardly internally tapering sleeve 32 is threaded into an opening formed in the under side of the carriage 14.

A plurality of perforations 11a formed in the base 11 are arranged concentric the axis of the sleeve 32 and longitudinally sliding clamps 33, 34 and 35 having V-shaped clamping end portions are mounted upon the base 11 in a manner facilitating the gripping of a casting ring therebetween substantially as shown in Fig. 8. The clamps 33 and 34 it will be noted can be held in position by wing nuts 36 and 37 respectively and the clamp element 35 can be held in position or adjusted as the case may be by means of a screw 38 receivable within parts of the base 11. A sliding guide member 35a is provided to prevent rotation of the clamp element during adjustment of the screw 38.

Referring now particularly to Figs. 6 and 7 it will be noticed that trunnions 39 extending outwardly from sides of the carriage 14 receive hook elements 40 formed in end portions of a stirrup frame 41 which hangs downwardly from the carriage substantially as illustrated. A screw 42 manually operable by means of a wheel 42a carries on its upper end a cup 43 adapted to receive the bottom end portion of the internally upwardly tapered sleeve 32 hereinabove described. It is to be noted that the interior of the cup includes a centrally located upstanding bump which projects into the open end of the sleeve for purposes which will hereinafter be described. The well portion 43b of the cup 43 is spaced with respect to the sides of the sleeve 32 and terminates at its base in a trough 43c communicating with the interior of the cup by radially extending openings formed near the base of the cup walls.

Having described the structural features of the novel casting machine according to the present invention its preferred mode of operation next will be described during the course of which reference will be made to the numbered parts of the figures of the drawings and particularly to Fig. 8. Assuming the device assembled as described, a first step in use is disengagement of the link 25 from the joint 24 whereby the lever arm 17 can be raised upwardly and backwardly and the carriage 14 removed from the standards 13. The carriage is inverted and placed upon a suitable support and wet fibrous material such as asbestos or the like is pressed within the sleeve 32 by means of a pestle or similar appropriate tool causing the matted fibrous material to be distributed within the sleeve and across the mouth thereof substantially as shown in Fig. 8 wherein the main body of the fibrous material within the sleeve 32 is designated by the reference character A and the matted ma-

5 terial around the mouth of the sleeve by the reference character A'. It is to be noted that a cavity A'' is formed in the surface of the matted fiber for purposes which hereinafter will be more fully described.

When the matted fibrous material has been so disposed within the sleeve final pressing is accomplished preferably by use of the stirrup frame and cup illustrated in Figs. 6 and 7. In this instance appropriate quantities of wet fibrous material if necessary are placed within the cup 43 and the cup advanced against the open bottom end of the sleeve 32 by rotation of the screw 42. It is to be noted that moisture pressed from the fiber will now collect in the trough 43c from edge portions of the cup 43 thereby preventing overflow of moisture onto the base of the device when the final pressing takes place after the carriage 14 has been returned to its position upon the standard 13.

Assuming the matted material has been pressed within the sleeve 32 as described and a casting ring B having a mold C formed in an investment D within said ring is held in the sliding clamps 33, 34, and 35 above described, the carriage is moved downwardly by manipulation of the lever 17 after connection of the link 25 with the joint 24 whereby the bottom of the sleeve 32 registers with and closes the open top of the casting ring B. In this manner the moisture matted fibrous material A is brought in close proximity to superheated metal located in the inverted conical cavity formed in the top of the investment and, inasmuch as a sealed chamber is provided by engagement of the sleeve end with the casting ring, moisture vaporized from the matted fiber produces steam which forces the molten metal into the mold cavity C causing complete penetration of the interstices thereof and assuring faithful reproduction in the molded object of the contour of the mold. It is preferred that the pressure applied by means of the lever 17 be continued until the molded metal has hardened.

It is to be understood that this invention is 45 capable of extended application and is not confined to the precise illustrated forms nor described construction and, therefore, such changes and modifications may be made therein as do not affect the spirit of the invention nor exceed the scope of the appended claim.

Having thus described the present invention, what it is desired to secure by Letters Patent is:

A device for casting dental inlays, comprising a flat base having a central foraminous portion; 55 two oppositely arranged uprights carried by the base on the outside of the foraminous portion, horizontally adjustable clamping means carried by the base for adjustably holding a casting ring on the foraminous portion of the base, a carriage 60 vertically movable on said uprights, means carried by the carriage for holding the same in its adjusted position on the uprights, a standard carried by the base beyond the uprights, a lever pivotally connected to the standard and straddling the uprights, a link interposed between the carriage and the lever and having ball and socket connections with the same, a tapering sleeve mounted on the underside of the carriage adapted to form sealing engagement with a casting ring held on said base.
